WILLIS A. GIBBONS, OF MONTCLAIR, NEW JERSEY, ASSIGNOR TO MORGAN & WRIGHT,
OF DETROIT, MICHIGAN, A CORPORATION OF MICHIGAN

METHOD AND APPARATUS FOR MANUFACTURING RUBBER ARTICLES

Application filed March 13, 1928, Serial No. 261,196. Renewed October 22, 1929.

This invention relates to a method and apparatus for the manufacture of hollow rubber articles such as inner tubes for vehicle tires, but more particularly to the formation 5 of such articles directly from a rubber latex or other aqueous dispersion thereof by the direct deposition of the rubber on a form or mandrel, and has for its primary object to provide a simple and effective method of producing a superior article.

Further objects are to provide a simple and durable form or mandrel construction on which the rubber may be uniformly deposited and which may be withdrawn from 15 the article after such article is completely formed; to provide a method of making inner tubes as a complete annulus requiring no splicing or joining, to provide a hollow sectional form which will insure uniform depositing of the rubber on the surface thereof, to provide adequate means for quickly and completely draining the form after the rubber has been deposited on the surface thereof, to provide means for accurately positioning 25 the various sections of the form and locking the same in assembled position, to facilitate the removal of the formed article from the form or mandrel, and in general to provide an improved means of manufacturing articles 30 of rubber.

The many other objects and advantages of the invention will be better understood by reference to the following specification when considered in connection with the accompanying drawing illustrating a selected embodiment thereof in which:

Fig. 1 is a side elevation partially in section showing a form or mandrel embodying the principles of the invention;

Fig. 2 is an enlarged longitudinal section of a portion of the form or mandrel shown in Fig. 1; and

Fig. 3 is a similar section on the line 3—3 of Fig. 2.

Referring to the drawing, the mandrel or form 5 comprises a hollow inner shell 6 and a filter covering 7. The shell 6 is made of metal or other suitable shape-retaining material and comprises two sections 8 and 9 which are adapted to engage to form a complete

annulus. The covering 7 may be of any one of a number of different materials or a combination of such materials, and its primary function is to act as a filter for the rubber latex in a manner which will be presently described.

The section 9 fits between the ends of the section 8 and is adapted to be locked in position therein by slidable bolts 10 which are normally held retracted within the section 9 in a disengaged position by springs 11. These bolts are actuated to lock the sections in assembled position by a cam 12 on a substantially U-shaped pipe 13 which extends through a wall of the section 9 and is revoluble therein. The pipe 13 ends at its extremity against the wall opposite through which it enters the section 9. Bushings or collars 14 and 15 on this pipe coat with the walls of the section to prevent axial movement of the pipe while permitting free rotation thereof. The bolts 10 are reciprocable through the end walls of the section 9 into perforations 16 in the opposing end walls of the section 8, as illustrated in the drawing, to perform their locking function. Ribs 17 are provided on the end walls of the section 9 to fit within corresponding depressions 18 in the end walls of the section 8 to maintain the sections in proper position.

Communicating passages 19 connect the interiors of the assembled sections 8 and 9. Similar registering passages 20 are likewise provided and these communicate with a drain pipe 21 extending to the bottom thereof as at 22 where an opening 23, preferably of substantial size, is provided to insure complete drainage of the section, it being understood that the form shown is intended to stand in a vertical plane in use but of course may occupy other positions. Ports 24 may be provided in the collar 14 and the pipe 13 to provide for adequate drainage of section 9.

The pipe 13 is connected to a suitable source of vacuum or desired pressure (not shown) to provide a differential of pressure within and without the form or mandrel 5 which permits the rubber to be more rapidly deposited on the filter covering 7, as will be

presently described. This pipe is adapted to be swung to either side in the manner indicated in Fig. 3 to actuate the cam 12 and it also may be used to support the assembled form or mandrel during deposition.

The curved or side walls 25 and 26 of the sections 8 and 9 respectively are provided with a multiplicity of relatively small and evenly distributed openings 27, only a small number being indicated in the drawing in order to avoid confusion. Preferably, the end walls of the section are not of sufficient thickness to provide an expanse of metal or impermeable material which might interfere with the proper deposit of the rubber at this point, but any likelihood of this occurring may be overcome by providing diagonal perforations 28. The spacing of the perforations as 27 and 28 may vary considerably, but it is not advisable that this should be greater than two inches and a less distance is preferable. Openings one-eighth of an inch in diameter and spaced about one inch are suitable.

25 The particular material composing the filter covering 7 forms no part of the present invention, and any suitable material or combination of materials may be used, which will permit the passage of the aqueous portion 30 but not the rubber of the latex or dispersion. An advantageous form of covering for the shell 6 may be provided by overlaying the same with wrappings of fibres, cords, fabric, paper or other permeable material and

35 then applying to this a covering of filtering composition such as clay slip. A fabric strip may be applied to the joints between the sections and lightly covered with the filtering composition. Use of some reinforcing material throughout the filtering composition is advantageous as it renders the same more durable and less liable to be fractured, but is not essential.

40 The form or mandrel illustrated in the drawing may be prepared for use by turning the pipe 13 sidewise to withdraw the bolts within the section 9 and then lowering this section from the position indicated in dot and dash lines in Fig. 1 to the assembled 45 position, as shown in that figure, the lugs 17 acting to guide this movement. The pipe 13 is then turned to cause the cam 12 to force the bolts 10 into the corresponding perforations 16 in the section 8, thereby locking section 9 to section 8 and forming a 50 complete annulus. The shell thus formed is then covered partially or completely in the manner described with the fabric or other material and finally the filtering composition 55 is applied over the entire exposed surface.

60 After the form has been coated with the filtering composition, it is placed in a body of rubber latex or equivalent dispersion and 65 the area within the sections of the form is ex-

hausted through the pipe 13, thus creating a differential of pressure within and without the form. This causes the fluid of the rubber latex to filter through the filtering composition leaving the rubber deposited on the outside. When the deposit is of sufficient thickness, the form is removed from the latex. The fluid entering the form through the filtering material is sucked into the pipe 13 and carried away. The rubber is then dried on the form preferably with the vacuum still on, and on the completion of the drying, vulcanized. To remove the form from the inner tube the pipe 13 is turned sideways to release the bolts 10. Air under pressure is then introduced into the form through the pipe 13 and this causes the coating of rubber to be ballooned away from the form. The section 9 is now pulled through the hole in the rubber formed around the point where the pipe 13 passes into the section 9, after which the section 8 is withdrawn in the same manner, air under pressure being forced into the rubber annulus during this operation to facilitate the removal. Alternately or supplementarily 70 a slit may be cut in the deposit of any desired length to facilitate removal of the sections 8 and 9. Preferably the slit, if made, will pass through the hole formed by the pipe 13. For larger sizes of tubes, at least, it is deemed preferable to use a slit and where permissible to locate it in intersecting relation with the hole formed in the deposit by the pipe 13.

75 The usual valve base or patch may then be applied at the hole or slit which has been formed in the tube. If the slit be located in the side wall or periphery of the tube, as it may, it may be closed by patching with rubber in any suitable and convenient manner. Preferably but not necessarily, a vulcanizable cement is employed in applying the valve base and/or applying a patch to close the slit. The valve base may be applied to the form before the deposit is made, or to the deposit before it 80 has been dried. In such case, of course, it would be preferable to locate the slit for removal of the sections 8 and 9 at a point remote from the valve base and preferably in the outer periphery of the tube.

85 The valve stem may be applied and mounted to complete the tube for use in any suitable and convenient manner.

90 While as specifically disclosed, the inlet tubes providing pressure on the interior of the formed article or for evacuating the interior of the mandrel have been described as being applied only to the section 9, it is obvious that such pipes and connections might be applied to both sections 8 and 9 or to section 8 alone with satisfactory results.

95 It will be readily evident that the construction and arrangement of parts may be very materially modified by one skilled in the art without departing from the scope 100

of the invention and the particular embodiment herein shown and described was selected merely for the purpose of illustration. The principles involved in this invention are applicable to the manufacture of practically any hollow rubber article. The shape of the form and arrangement of the sections would naturally depend upon the particular article to be produced.

Having thus described my invention, what I claim and desire to protect by Letters Patent is:

1. A form for the manufacture of hollow endless rubber articles by the deposition of rubber from an aqueous dispersion comprising a plurality of apertured sections adapted when assembled to constitute an endless support, a covering of filtering material on said sections capable of passing the aqueous portion but not the rubber of the dispersion, at least one of said sections carrying a conduit for the application of sources of fluid pressure to the interior of the sections.

2. A form for the manufacture of hollow annular articles by the deposition of rubber from latex comprising a plurality of sections adapted when assembled to make an annulus, a stratum of material covering said sections capable of passing the aqueous portion but not the rubber of the latex, and a conduit communicating with the interior of one of the sections.

3. A form for the manufacture of hollow annular articles by the deposition of rubber from latex comprising a plurality of sections adapted when assembled to make an annulus, a stratum of material covering said sections capable of passing the aqueous portion but not the rubber of the latex, a conduit communicating with the interior of one of the sections, and means for holding said sections in assembled relation and disengageable for removal from the article.

4. A form for the manufacture of hollow annular articles by the deposition of rubber from latex comprising a plurality of sections adapted when assembled to make an annulus, a stratum of material covering said sections capable of passing the aqueous portion but not the rubber of the latex, a conduit communicating with the interior of one of the sections and adapted to form a hole in the deposited article, and means for holding said section in assembled relation and disengageable for removal from the article, said conduit being rotatably mounted in the section, and said means including spring actuated holding members, and a cam on said conduit for shifting the holding members against the operation of their springs.

5. A form for the manufacture of hollow annular articles by the deposition of rubber from latex comprising a plurality of sections adapted when assembled to make an annulus, a stratum of material covering said

sections capable of passing the aqueous portion but not the rubber of the latex, and a conduit communicating with the interior of one of the sections, said sections being provided with communicating passages.

6. A form for the manufacture of hollow annular articles by the deposition of rubber from latex comprising a plurality of sections adapted when assembled to make an annulus, a stratum of material covering said sections capable of passing the aqueous portion but not the rubber of the latex, a conduit communicating with the interior of one of the sections, said sections being provided with communicating passages, and means for 70 draining the interior of the sections.

7. A form for the manufacture of hollow annular articles by the deposition of rubber from latex comprising a plurality of sections adapted when assembled to make an annulus, a stratum of material covering said sections capable of passing the aqueous portion but not the rubber of the latex, a conduit communicating with the interior of one of the sections, said sections being provided with 75 communicating passages, and means for 80 draining the interior of the sections, said last named means including a pipe provided with an intake opening at substantially the lowermost point in the interior of the assembled sections.

8. A form for the manufacture of inner tubes by the deposition of rubber from an aqueous dispersion thereof, which consists of a plurality of engageable sections, means for 85 disengageably securing the sections in annular arrangement, means for supporting the annulus in a rubber dispersion so as to form a hole in the article at one point, and means of communication with the interior of the 90 form through the supporting means.

9. An internal annular form for the manufacture of inner tubes by the deposition of rubber from an aqueous dispersion thereof, which consists of two sections one of which is relatively short, means for disengageably securing the sections into an annulus, means for supporting the annulus in a rubber dispersion so as to form a hole in the article being deposited at only one point, and means 95 connected with the supporting means for 100 communication with the interior of the form.

10. That method of manufacturing rubber endless tubes which comprises effecting the deposition of the solid constituents of latex 110 upon the exterior surface of a continuous circular form giving mandrel, forming in the tube an aperture substantially smaller than a cross section of the mandrel, vulcanizing the rubber tube, and withdrawing the mandrel 115 through the aperture formed in the tube.

11. That method of manufacturing rubber endless tubes which comprises effecting the deposition of the solid constituents of latex 120 upon the exterior surface of a continuous 125

circular form giving mandrel, forming in the tube an aperture of area substantially smaller than the area of any cross section of the mandrel, vulcanizing the rubber at least to a degree sufficient to prevent rupture of the tube upon withdrawal of the mandrel through the aperture, and withdrawing the mandrel through the aperture.

12. That method of manufacturing rubber inner tubes which comprises effecting the deposition of the solid constituents of latex upon the exterior surface of a continuous circular form giving mandrel, forming in the rubber tube an aperture of a size approximating the size of a valve stem, vulcanizing the rubber at least to a degree sufficient to prevent rupture of the tube upon withdrawal of the mandrel therefrom through the aperture, withdrawing the mandrel through the aperture from the tube, and finishing the tube.

13. That method of manufacturing rubber inner tubes which comprises effecting the deposition of the solid constituents of latex upon the exterior surface of a continuous circular form giving mandrel having a projection adapted to form during deposition an aperture in the tube of a size to accommodate a valve stem, effecting the vulcanization of the rubber tube, withdrawing the mandrel through the aperture from the tube, and finishing the tube.

14. That method of manufacturing endless tubes which comprises effecting the deposition of the solid constituents of latex upon the exterior surface of a continuous circular form giving mandrel, forming in the tube an aperture substantially smaller than a cross section of the mandrel, vulcanizing the rubber tube, opening the mandrel, and withdrawing the mandrel through the aperture formed in the tube.

15. That method of manufacturing rubber endless tubes which comprises effecting the deposition of the solid constituents of latex upon the exterior surface of a continuous circular form giving mandrel, forming in the tube an aperture substantially smaller than the cross section of a mandrel, opening the mandrel, and withdrawing the mandrel through the aperture formed in the tube.

Signed at New York, N. Y., this 12th day of March, 1928.

WILLIS A. GIBBONS.
